UNITED STATES PATENT OFFICE.

WALTER E. HOSCH, OF ST. LOUIS, MISSOURI, ASSIGNOR TO MEASUREGRAPH COMPANY,
OF ST. LOUIS, MISSOURI, A CORPORATION OF MISSOURI.

WINDING-DRUM.

1,253,243.

Specification of Letters Patent.

Patented Jan. 15, 1918.

Original application filed February 8, 1915, Serial No. 6,671. Divided and this application filed October 7, 1916. Serial No. 124,241.

To all whom it may concern:

Be it known that I, WALTER E. HOSCH, a citizen of the United States, residing in the city of St. Louis and State of Missouri, have invented new and useful Improvements in Winding-Drums, of which the following is a specification.

This invention relates to a winding device or drum about which a cord, ribbon or web of any kind may be wound. Although the invention may be used for various purposes, it is particularly applicable when used with machines for measuring lengths of ribbon, lace or other articles in the form of a web. 10 The present specification is a division of my application, Serial No. 6671, filed February 8, 1915, for a ribbon measuring, cost computing and winding machine. When applied to such a machine the drum facilitates the running off of the ribbon from the supply roll, and after the ribbon is cut off it enables the measured quantity of the ribbon to be readily removed from the drum.

The general object of the invention is to produce a drum for this general purpose having a very simple construction which will facilitate the winding off of a web or ribbon to form a roll on the drum, and enabling this roll to be quickly removed from the drum 20 when desired.

In the drawing which illustrates the preferred embodiment of my invention,

Figure 1 is a plan partially shown in section of a machine of the type to which I refer, and illustrating my drum applied to it,

Fig. 2 is an end elevation of this machine,

Fig. 3 shows the appearance of a cross section taken through the drum, and

Fig. 4 is a detail longitudinal section at 40 the free end of the drum.

Referring more particularly to the parts, 1 indicates the housing of a winding and measuring machine of the type referred to above. This housing is extended on one side so as to form a trough or cradle 2 adapted to receive a bolt or supply roll indicated by the dotted line 3, of any material such as lace or ribbon which is to be run off in small quantities and measured. In the operation 45 of this machine the web from the supply roll 3 is drawn through a throat 4 and between rollers 5 and 6 in this throat, which co-operate with a measuring mechanism to measure

the length of web which passes through the throat.

On the side of the machine opposite to the cradle 2 my drum 7 is located. I prefer to rotatably support this drum 7 by securing it to a stub shaft 8 which is rotatably mounted in a bearing 13 in an extension of the 55 housing 1. The stub shaft 8 may be rotated in any desired manner, for example, by means of a large gear 9 which drives a pinion 10, the large gear being rotated when desired by a suitable crank 11.

This drum comprises a head portion 12 which lies adjacent to the bearing 13. The body portion of this drum comprises a plurality of circumferentially disposed members, sections or fingers 14, which may be 60 supported from the head 12 in any desired manner. These fingers 14 extend longitudinally of the drum from the head portion 12 and the spaces between them form longitudinal gaps or recesses 15 extending in from 65 the free end of the drum. Obviously, these fingers 14 may be constructed separately, and individually attached to the head 12, but I have illustrated them as formed integrally, that is, as cut from a tubular shell by cutting 70 longitudinal slots which form the gaps 15. In either case they are held by the head 13 rigidly against lateral movement only. The material out of which these fingers are formed is preferably resilient metal such as 75 spring steel or brass, and the tips 16 of the fingers preferably turn inwardly slightly; also these fingers are curved in a transverse direction so that they form sections of the circumference of the cylindrical drum wall 80 (see Fig. 3). By reason of the convex form of the outer sides of the fingers 14 they operate to produce a substantially cylindrical wall for the drum, thereby avoiding any edges or places on the drum that would bend 85 the ribbon about an angle and crease it when wrapped upon the drum. This is most desirable where the device is used for winding off delicate laces or ribbons.

While I do not limit myself to the specific 100 form of drum described, the members 14 which form sections of the drum, however, should be movable inwardly. This effect is very simply attained by the construction set forth, for it is evident that if the fingers or 105 drum sections 14 are compressed, that is,

pressed inwardly, the body portion of the drum will collapse or become reduced in diameter.

In the operation of the device, the end of the web is passed under one of the tongues or fingers 14 by passing it through two adjacent gaps 15. Now when the crank 11 is rotated in the proper direction the stub shaft 8 will rotate and thereby rotate the drum. When a desired quantity of the ribbon, or the like, has been wound onto the drum to form a roll on the drum, the ribbon may be cut off at the slot 17. The roll of ribbon or web upon the drum may then be removed simply by compressing or squeezing the free ends of the drum sections 14 inwardly, whereupon the roll of ribbon may be slipped longitudinally off the outer end of the drum.

20 In practice the drums may be constructed with the stub shaft attached, or with other means enabling them to be sold separately for convenient attachment in the machine.

It is understood that the embodiment of the invention described herein is only one of the many embodiments this invention may take and I do not wish to be limited in the practice of the invention nor in my claims to the particular embodiment set forth.

30 What I claim and desire to secure by Letters Patent is:—

1. In a machine of the class described, a winding drum having a head rotatably supported, and having a plurality of circumferentially disposed fingers supported solely by said head, and extending longitudinally of the drum, about which a web may be wound to form a roll on said drum, said fingers operating to yield inwardly at their free ends when compressed to permit the roll to be slipped longitudinally off of the end of said drum.

2. In a machine of the class described, a

winding drum rotatably supported at one end, and having a body portion of tubular form, said body portion having a plurality of longitudinally disposed slots formed therein dividing said tubular portion circumferentially into compressible sections enabling the web to be wound in a roll on said drum, and then slipped longitudinally off of the other end of said drum by compressing the body portion of said drum.

3. As a new article of manufacture, a winding drum having a single head for supporting a drum at one end only, and having a substantially tubular body composed of a plurality of circumferentially disposed members about which the web may be wound to form a roll on the drum, said members being supported by said head, and inwardly movable at their free ends to permit the roll to be slipped longitudinally off the end of the drum.

4. In a machine of the class described, a winding drum having a single head rotatably supported and having a plurality of circumferentially disposed fingers supported solely by said head, and forming a substantially tubular body about which a web may be wound to form a roll on the drum, said fingers operating to permit the roll to be slipped longitudinally off of the end of the drum.

5. In a machine of the class described, a winding drum rotatably supported at one end and having a plurality of circumferentially disposed convex members forming a cylindrical wall about which a web may be wound to form a roll, the ends of said members being free and inwardly movable to permit the roll to be slipped longitudinally off of the end of the drum.

In testimony whereof, I have hereunto set my hand.

WALTER E. HOSCH.
